(57) **CLAIM**

I claim the ornamental design for a display screen with financial institution communication interface, as shown in the drawings.

DESCRIPTION

FIG. 1 is a first image in a sequence for a display screen with financial institution communication interface showing the new design;

FIG. 2 is the second image thereof;

FIG. 3 is the third image thereof;

FIG. 4 is the fourth image thereof;

FIG. 5 is the fifth image thereof;

FIG. 6 is the sixth image thereof; and,

FIG. 7 is the seventh image thereof.

The broken-line rectangle illustrates the perimeter of a display screen. The broken lines form no part of the claimed design. The appearance of the transitional graphical user interface sequentially transitions between the images shown in FIGS. 1-7. The process or period in which one image transitions to another image forms no part of the claimed design.
